Primary Examiner — Sheryl Lane*Assistant Examiner* — Mark T. Philippss(74) *Attorney, Agent, or Firm* — Wayne & Ken, LLC; Tony Hom(57) **CLAIM**

The ornamental design for a micro-electric grinding machine, as shown and described.

DESCRIPTION

FIG. 1 is a perspective view of a micro-electric grinding machine showing my new design;

FIG. 2 is a front elevation view thereof;

FIG. 3 is a back elevation view thereof;

FIG. 4 is a left side view thereof;

FIG. 5 is a right side view thereof;

FIG. 6 is a top plan view thereof; and,

FIG. 7 is a bottom plan view thereof.

The broken lines in the drawing depict environmental subject matter only and form no part of the claimed design.
